UNITED STATES PATENT OFFICE

104,520

DESIGN FOR A CUFF LINK

James F. Allison, Providence, R. I., assignor to
Freeman-Daughaday Company, a corporation
of Rhode Island

Application April 13, 1937, Serial No. 68,731

Term of patent 14 years

To all whom it may concern:

Be it known that I, James F. Allison, a citizen
of the United States, residing at Providence, in
the county of Providence and State of Rhode
Island, have invented a new, original, and ornamental
Design for a Cuff Link, of which the following
is a specification, reference being had to
the accompanying drawing, forming a part
thereof.

Fig. 1 is a top plan view; and

Fig. 2 is a side elevation of a cuff link showing
my new design.

The dominant feature of the design is shown
in full lines.

I claim:

The ornamental design for a cuff link substan-

tially as shown and described.

JAMES F. ALLISON.
